UNITED STATES PATENT OFFICE.

DAVID LEVIGTON, OF NEW YORK, N. Y.

DESIGN FOR AN EASEL.

Application filed July 8, 1924. Serial No. 10,084. Term of patent 3½ years.

To all whom it may concern:

Be it known that I, DAVID LEVIGTON, a citizen of the United States, and a resident of New York, borough of Bronx, in the county of Bronx and State of New York, have invented a new, original, and ornamental Design for an Easel, of which the following is a specification, reference being had to the accompanying drawing, forming part thereof, in which—

The figure is an elevation of the front of an easel showing my new design.

I claim:—

The ornamental design for an easel, as shown.

DAVID LEVIGTON.
